UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

DESIGN FOR A LIGHTING-FIXTURE.

47,531.

Specification for Design.

Patented July 6, 1915.

Application filed May 14, 1914. Serial No. 838,583. Term of patent 14 years.

To all whom it may concern:

Be it known that I, REUBEN B. BENJAMIN, a citizen of the United States, residing at Chicago, in the county of Cook and State of Illinois, have invented a new, original, and ornamental Design for Lighting-Fixtures, of which the following is a specification, reference being had to the accompanying drawing, forming a part thereof.

The figure is a perspective of a lighting fixture showing my design.

I claim:

The ornamental design for a lighting fixture as shown.

REUBEN B. BENJAMIN.
